RADIO CONTROL SYSTEM

Ellison S. Purington, Gloucester, Mass., assignor, by mesne assignments, to Radio Corporation of America, New York, N. Y., a corporation of Delaware

Original application May 18, 1944, Serial No. 536,104, now Patent No. 2,465,925, dated March 29, 1949. Divided and this application June 29, 1945, Serial No. 602,235

11 Claims. (Cl. 250—20)

1

This application is a division of my copending U. S. application Serial No. 536,104 filed May 18, 1944 entitled "Radio control system," now Patent No. 2,465,925 granted March 29, 1949, assigned to the same assignee as the instant application.

This invention relates to a radio control system suitable for use in ultra-high frequency channels and has for an object to provide a system of the above type adapted for radio dynamic control or for communication purposes, which is highly selective and which has characteristics such that it is free to a high degree from interference.

Another object is to provide a system of the above type having novel and improved details of construction and features of operation.

Various other objects and advantages will be apparent as the nature of the invention is more fully disclosed.

The present system utilizes two channels in the ultra-high frequency range, such as in the range of 400 to 1000 megacycles, and provides for the transmission of short, timed pulses on the two channels which may be varied as to sequence in accordance with the desired control or signal. The system utilizes a pulse transmitter which is capable of transmitting short pulses of comparatively high power.

A radiant energy pulse is sent from the transmitter to the receiver on one channel followed by a radiant energy pulse on the other channel. There is a frequency separation between the two channels on which energies necessary for operation are sent, and there is a time separation between the arrival of the two energies at the receiver. The freedom from interference depends largely upon the amount of frequency separation of the channels and upon the amount of time separation of the energies on the channels. A most important factor is the use of transmitter energies in the form of short dots or pulses with very high peak radiant power, and with relatively long intervals between the pulses.

By the combination of pulse type transmission, two radiant energy channels and different times of transmission of the energies on the two channels, an extremely high degree of security is provided.

In the present system the pulses may be from 10 to 50 microseconds in length. The time interval between the pulses is several times the length of the pulses themselves, for example, about 5 to 20 times the length of the pulses and successive pairs of pulses are separated by a space having a duration several times the interval between the

5 pulses themselves, for example, 20 to 100 times said time interval.

The control may be responsive to the receipt of a single pair of pulses. Hence the complete transmission may be of extremely short duration, which renders its interception and freedom from interference signals extremely difficult. However, the transmissions may extend over a plurality of pairs of pulses if desired, in which case, accidental interference with one or more of the pairs of pulses would not affect the control.

While it is known to be physically possible and practicable to produce high peak power on a narrow radio band over a short duration of time, it 15 is not practicable to produce a comparable high peak power over both a wide radio band and over a long duration of time, as would be necessary for successfully overcoming strong interference signals. Ordinary, non-pulse transmitters would 20 not be capable of interfering successfully with the control because sufficient power would not be available to produce a response at the receiver matching in intensity the pulse from the pulse transmitter. On the other hand, with a pulse 25 transmitter it would be very unlikely that the interfering pulse would coincide in time with a control pulse, or that its rate of recurrence would correspond to that of the control pulse as would be required to produce interference on succeeding 30 pulses. For high speed telegraphic purposes, for example, a single dot or dash might occasionally be obliterated by interference, but for slow speed or radio control purposes, this amount of interference would be entirely negligible.

35 In accordance with the present invention, a pulse forming circuit is designed to form a succession of pairs of spaced pulses. The pulses of each pair are separated and are used individually to modulate radio transmitting means operating 40 on two different channels, the first pulse of each pair being connected to modulate the transmitter on one channel and the second pulse of each pair being connected to modulate the transmitter on the other channel. Selective means is provided in 45 the modulating circuit so that the first pulse of each pair may be applied to either channel at will and the second pulse may be applied to the other channel. In this way, the pulses are radiated over the two channels with a frequency sequence determined by the selective means and with a time interval determined by the original pulse forming circuit.

50 In a specific embodiment of the invention the pulses in the two channels are received by separate receivers tuned to the respective channels

and containing the usual detector circuits to make the pulses available in an output circuit. The outputs of the two receivers are connected to a timing comparator which is designed to be responsive only when the pulses are received with a predetermined time spacing.

In one embodiment the timing comparator includes a pulse stretching circuit which is arranged to stretch the pulse from one of the receivers so as to cause the same to overlap in time the pulse from the second receiver when the first pulse is received a predetermined time interval before the second pulse. The combined effect of the two pulses, when they are thus caused to overlap, is utilized to actuate an output relay circuit. When only a single pulse is received or when the pulses are not received in proper time sequence to cause the same to overlap in the output circuit of the comparator no response is produced.

The effect of two overlapping pulses separately applied to the timing comparator is to produce a single pulse of a duration equal to the amount of time of overlap. This can be applied to a relay system operative on a single pulse, as for example a gaseous type electronic relay, which however requires a reset device such as the use of A. C. plate supply if the control operation is to be repeated. While this is satisfactory for some purposes, it is in general preferable to actuate the control from the combined effect of a considerable number of recurrent pulses giving additional security by electrical tuning to the recurrence rate.

Instead of utilizing two separate receivers the incoming radiant energy may be received in a single receiver tuned to respond to both channels. The receiver will then include suitable pulse separation means to separate the pulses received in the respective channels and to apply them to the timing comparator above outlined.

Although the novel features which are believed to be characteristic of this invention are pointed out more particularly in the claims appended hereto, the invention will be better understood by referring to the following description, taken in connection with the accompanying drawings in which certain specific embodiments thereof have been set forth for purposes of illustration.

In the drawings:

Figure 1 is a block diagram indicating the general arrangement of a transmitter and receiver embodying the present invention;

Figure 2 is a schematic diagram of a timing comparator circuit for use in the receiver of Fig. 1; and

Figure 3 is a schematic diagram of a pulse receiver utilizing a single radio receiver tuned to both channels and a pulse separating circuit actuated thereby.

In the drawings, the radio transmitter and receiver circuits and the tube circuits are shown only in such detail as is necessary to an understanding of the present invention and it is to be understood that the circuits are otherwise of standard and well known form and include the various potential sources and control elements which are well known in the art.

FIGURE 1

Referring to Fig. 1, the block 10 represents a pulse forming circuit the details of which are not here shown and which is adapted to produce a series of spaced pairs of pulses *a* and *b* and to separate the pulses of each pair as indicated in separate circuits terminating at terminals 11 and

12 respectively and having a common ground terminal 13. The pulse *a* of each pair of pulses on terminal 11 is assumed to precede the pulse *b* on terminal 12 although this sequence may be reversed if desired.

The terminals 11 and 12 are connected to poles 14 and 15 respectively of a double pole double throw, reversing switch 16 the stationary contacts of which are connected by lines 17 and 18 respectively, to the input circuits of radio transmitters 20 and 21 respectively. The radio transmitters 20 and 21 are preferably of the shortwave pulse type and are adapted to radiate carriers on frequencies f_1 and f_2 amplitude modulated respectively by the pulses *a* and *b*. The transmitters may be designed to radiate only when a pulse is received from the pulse forming circuit 10, so that the energy radiated constitutes a series of spaced pulses occurring first on the frequency f_1 and then on the frequency f_2 for switch position R, or vice versa for switch position L.

The pulses radiated by the transmitters 20 and 21 are received by the receivers 22 and 23 respectively which are preferably of the superheterodyne type terminated with detectors to produce pulses in their output circuits indicated by the terminals 24, 25, 26 and 27. The terminal 24 of the receiver 22 is connected by a line 30 to an input terminal 31 of a timing comparator 32, the details of which are shown in Fig. 3. The terminal 26 of the receiver 23 is connected by a line 33 to an input terminal 34 of the timing comparator 32. The terminals 25 and 27 are indicated as connected by a line 35 to ground and to a common input terminal 36 of the timing comparator 32.

The timing comparator 32 includes circuits to be described which are selected so that when the pulse on channel f_1 precedes the pulse on channel f_2 , a right relay 39 is energized and when the pulse on the channel f_2 precedes the pulse on the channel f_1 a left relay 38 is energized. These relays are provided with armatures 41 and 40 respectively which are adapted to close work circuits which may constitute selective control for mobile objects such as right and left steering controls or a speed control or a suitable signalling circuit, such as an automatic dot-dash receiver.

The arrangement therefore is such that the relays 38 and 39 will be selectively actuated in accordance with the direction of closure of the switch 16 which controls the sequence of the pulses on the two channels. The switch may, of course, take the form of a push-button, key, or other suitable device which is readily operated for control or signalling purposes.

The timing comparator circuit 32 is preferably designed so that no operation results unless and until both pulses are received and unless the pulses are of sufficient duration and length and are spaced within the specified time limits. In addition, the system may be designed to respond only when the pulses on the two channels are repeated with a recurrence rate within specified limits. In this way the system is made highly selective and free from interference.

Receiving apparatus

The waves radiated from the transmitters 20 and 21 of Fig. 1 are shown as received by the receivers 22 and 23 which are tuned to the respective wave frequencies and are of standard construction to make the received pulses available in the output circuits of a detector. The detectors are of a type which will supply positive pulses at terminals 24 and 26 with respect to ground

terminals 25 and 27. These pulses are supplied to the circuits including input terminals 31 and 34 of the timing comparator 32. The pulse at the terminal 31 either precedes or lags behind the pulse at the terminal 34 depending upon the sequence of the transmitted pulses. The circuit for the timing comparator 32 is shown more in detail in Fig. 2.

FIGURE 2

Referring now to Fig. 2, the terminal 31 is connected by a line 160 to a resistor 161 in the input circuit of an amplifying triode 162. The terminal 34 is connected by a line 163 to a resistor 164 in the input circuit of an amplifying triode 165. The return leads from the resistors 161 and 164 are connected to the terminal 36. The plates 300, 301 of the triodes 162 and 165 are fed through resistors 166 and 167 respectively from a line 168 connected to a source of plate potential shown as a battery 170. For simplicity of construction, the triodes 162 and 165 may be housed in a common envelope, as may other triodes of the Fig. 2. They will be described however for convenience as independent tubes.

The pulse output of the tube 162 is fed through a condenser 171 to the control grid 302 of a tube 172. The plate 303 of tube 172 is connected through a condenser 173 to the control grid 304 of a tube 174. The cathodes of the tubes 172 and 174 are connected to ground through a biasing battery 175. The plates 303, 305 of the tubes 172 and 174 are connected to the line 168 through resistors 176 and 177 respectively. The plate 305 of the tube 174 is also connected through a resistor 178 with the control grid 302 of the tube 172 and through a resistor 179 and a condenser 180 to the control grid 306 of a key tube 181. The output circuit of the amplifier tube 165 is connected by a line 182 through a resistor 183 to the control grid 307 of an amplifier tube 184. The plates 308, 309 of the tubes 181 and 184 are connected in parallel through a resistance 185 to the line 168.

The tubes 172 and 174 and associated circuits constitute in effect a multivibrator circuit pulse stretching system which operates when energized by a short negative pulse on the input grid terminal of tube 172 to produce a negative pulse of longer duration and in the same sense on the output circuit of companion tube 174. The output of one tube shown as tube 172 is capacity coupled to the input of the other tube 174 as in a multi-vibrator, but the output of the tube 174 is directly coupled to the input of the tube 172 as in an electrical toggle. This system has one stable equilibrium position in the absence of signals. When the condition of stable equilibrium is momentarily upset, as by a pulse on grid 302 of tube 172 from the plate 300 of tube 162, the system does not instantaneously return to the equilibrium condition, because of the energy change in condenser 173 during the pulsing. As a result the plate current of output tube 174 continues to change after the pulse on tube 172 has passed.

In the embodiment shown in the equilibrium condition tube 174 is biased to below cutoff by battery 175, while tube 172 passes current due to the positive voltage on its grid 302 derived from battery 170 through resistors 177 and 178. A positive pulse applied from terminal 31 to ground upon amplifier 162 causes a negative pulse to be applied from the output of tube 162 upon the

grid 302 of tube 172. In the equilibrium condition with no current flowing to or from the condenser 173 its lower plate is at ground potential and its upper plate is at the potential of the line 168 diminished by the very heavy drop through resistor 176 to the plate 303 of the current carrying tube 172. When now the negative pulse is impressed upon the control grid 302 of tube 172, the plate current is momentarily diminished toward or to zero, thereby decreasing the voltage drop in resistor 176 and increasing the potential on the upper plate of condenser 173. This tends to make the upper plate of condenser 173 more positive by a charging current to the condenser from the plate 303 of tube 172, and this charging current, represented in the condenser as a displacement current, causes corresponding current to flow from the lower plate of condenser 173 to ground through the grid resistor 310. As a result, both the upper plate and lower plate of the condenser 173 are raised to a higher potential, and the grid 304 of tube 174 which is connected to the lower plate of condenser 173 is quickly raised to the potential of the cathode of tube 174 or higher. This in turn increases the current flow to the plate 305 of tube 174, thereby lowering its plate potential due to the increased drop through resistor 177. Due to the direct coupling from plate of tube 174 to ground through resistor 178, the lowering of plate voltage of tube 172 drives its grid negatively in the same sense as the original pulse. If condenser 173 were of infinite capacity, the grid 302 of tube 172 would continue to be held negative, so that the controlling pulse from tube 162 would be followed by a permanent holding pulse from tube 174. However due to the capacity of condenser 173 being finite, the potential across condenser 173 changes in accordance with the voltage and resistance in its external circuit. With the grid of tube 172 driven negatively beyond cutoff, making tube 172 currentless, condenser 173 is charged to increase its voltage toward the limiting value of battery 170. But as it approaches this value, the charging current diminishes, decreasing the current through the grid-to-cathode and grid-to-ground path for tube 174, so that tube 174 commences to draw less current. As a result the potential of tube 172, until now held below cutoff after the control pulse from tube 162 has passed, approaches the cutoff point. When during the charging of condenser 173 by a current through resistor 176, the cut-off point of tube 172 is reached, and it commences to pass plate current also through the resistor 176, the charging of condenser 173 is checked due to the lowering of voltage applied to the top plate of condenser 173, the grid voltage of tube 172 drops toward zero and due to the coupling from tube 174 to tube 172 the action of causing tube 172 to pass plate current is accelerated. With the charging of condenser 173 checked, the operation of the tubes is such as to cause the condenser to discharge to its equilibrium condition. During this discharge operation, the voltage on the grid 304 of tube 174 is highly negative beyond cutoff, so that equilibrium is reached with no further change in plate current of tube 174.

By this action, the negative pulse impressed for a short time by the tube 162 upon the grid of tube 172 causes an extended positive pulse to appear on the grid of tube 174, and an extended negative pulse to be impressed from the plate of tube 174 onto the grid 306 of tube 181.

The alternating current output of the ampli-

7
fying tube 165 is transmitted through line 122 and resistor 183 to the control grid 307 of triode tube 184. Consequently through the action of tubes 162, 172 and 174, a positive pulse applied to terminal 31 causes a negative pulse with the same starting time, but of longer duration to be impressed upon the input of tube 184. Also by the action of tube 165, a positive pulse applied to terminal 34 causes a corresponding un-stretched negative pulse to be impressed upon the input of tube 184. By suitable choice of the resistors and the condenser 113 associated with pulse stretching tubes 172 and 174, the pulse on tube 181 may be caused to last longer than the time interval between pulses on terminals 31 and 34. Therefore in the event that terminal 31 is pulsed first and terminal 34 later, within a predetermined time limit established by the action of tubes 172 and 174, overlapping pulses will be impressed on the two tubes 181 and 184. If however terminal 34 is pulsed first then the pulse on tube 184 will have passed before the pulse on tube 181 starts, and there will be no overlap of these pulses.

The tubes 181 and 184 are coincidental key tubes, and in the embodiment shown they are triodes, with the cathodes connected together and grounded by a line 311 and with the plates 308, 309 connected together and fed from the line 168 through the resistor 185. The plates 308, 309 are direct coupled through resistor 190 to the grid 312 of a clipper tube 191 having its cathode biased positive with respect to ground by a battery 313 and its plate 314 fed from the line 168 through a resistor 193. The grid 312 of tube 191 is positively biased by the direct current flowing through resistors 185 and 190 and through the grid resistor 315 to ground, but the cathode battery 313 biases the cathode of tube 191 to a much higher potential than its grid, so that as a net result, tube 191 is biased considerably beyond cut-off so that normally no plate current flows through resistor 193.

Circuit conditions are so adjusted that no current passes through resistor 193 until the grids of both tubes 181 and 184 are very considerably negative. In the absence of a pulse on tube 181 for example, cutoff of tube 184 by a negative pulse will cause a change of plate current through resistor 185, but no effect in resistor 193. Only when the pulses on tubes 181 and 184 are coincidental will there be a pulse through resistor 193.

It is possible to utilize the pulse through resistor 193 to trigger off a gaseous relay tube, but in the present embodiment, use is made of the fact that the pulses established in resistor 183 are of a recurrent nature.

The plate 314 of clipper tube 191 is connected through condenser 194 to the grid 316 of amplifying triode 195, which in turn is connected to ground by a resistor 317 and condenser 318 in parallel. The cathode of the triode amplifier 195 is grounded by line 319 and its plate 320 is connected to line 168 through a plate resistor 321. The plate 320 of tube 195 is coupled through a condenser 322 to the anode 323 of a rectifier 200, the cathode of which is connected to ground through resistor 201, bypassed by a condenser 324, and also is connected to the grid 325 of a relay tube 202. A resistor 326 connected from the anode 323 of rectifier 200 to ground provides a D. C. return path for rectifier 200. The plate 327 of relay tube 202 is connected to the winding 39 of a relay 328, the other side of which is connected to line 168,

and the cathode of relay tube 202 is positively biased by a battery 329 so that no plate current will flow unless there is current passing through resistor 201 due to action of the rectifier 200. The relay 328 is provided with an armature 41 for closing an external work circuit.

The constants of the circuit associated with amplifier 195 are so chosen that it selectively integrates and amplifies the pulse power derived from the plate of clipper tube 191. This produces a wave form with high proportion of energy content in the fundamental rate of pulsing which is impressed on rectifier 200. This wave form is rectified, and smoothed out by the cathode-condenser 324 of tube 200, and the D. C. component of the rectified current raises the grid of relay tube 202 to cathode potential causing plate current to flow and attract the relay armature 41.

In the operation of Figure 2, thus far discussed, when upon closure for example of switch 16 to position R a positive pulse is impressed upon terminal 31 with respect to ground terminal 36, followed by a positive pulse upon terminal 34 within a predetermined time limit, amplifier 162 of Fig. 2 impresses a negative pulse upon pulse stretching circuit involving tubes 172, 174 and resulting in a negative pulse of longer duration impressed upon the grid 306 of coincidental key tube 181. The duration of this pulse overlaps the time interval at which a negative pulse is impressed upon coincidental key tube 184 due to the later pulse received from tube 165. By the coincidental action of tubes 181 and 184, clipper tube 191 is pulsed positively so that a pulse flows in the plate resistor 193 during the interval of overlap. This pulse is broadened, integrated and amplified by tube 195 and rectified by tube 200 to cause operation of the relay armature 41.

In the alternative event that switch 16 of Fig. 1 is thrown for example to position L the pulse on terminal 34 precedes that on terminal 31 the circuit above described will operate to produce pulses in resistor 185 which are insufficient to cause operation of the clipper tube 195. For utilizing the possible control corresponding to terminal 34 being pulsed before terminal 31, a companion circuit 209 is provided. This may be of the same general construction as that previously described, with corresponding parts designated by like numbers but followed by the letter *a*. However terminal 34 is connected to drive the grid of tube 162a and terminal 31 is connected to drive the grid of tube 165a. Therefore the pulse delay circuit 209 responds to a pulse on terminal 34. The output of circuit 209 includes a relay 328a with armature 40.

In this manner, the circuit of the timing comparator of Fig. 2 provides for operation of left relay 328a when the switch 16 is closed to position L which pulses channel *f*₂ before *f*₁ and it provides for closure of right relay 328 when the switch 17 is closed to position R which pulses channel *f*₁ before *f*₂.

FIGURE 3

In the system shown in Fig. 1 two independent receivers 22 and 23 are provided which are tuned respectively to the channels *f*₁ and *f*₂. Fig. 3 shows a circuit for receiving both channels on a single intermediate frequency type receiver and separating the pulses for application to the timing comparator. Referring to Fig. 3, the

block 210 indicates a receiving circuit which is tuned broadly to receive the two channels f_1 and f_2 . A single frequency local oscillator 211 and a detector 212 are connected to make the two pulses available as intermediate frequency pulses in an output circuit transformer 215 tuned to both intermediate frequencies in a well known manner. These pulses are supplied through the transformer 215 to an amplifier tube 216, the output circuit of which is connected to a well known type of frequency discriminating circuit 217 which includes coupled inductors 218 and 219 forming parts of a coupled circuit system and connected at their midpoints through a condenser 220. The midpoints of the inductors 218 and 219 are also connected through a resistor 222 and an inductor 223 to the return lead 224 of the amplifier tube 216.

The frequency discriminating circuit 217 has characteristics such that one of the pulses, for example, the intermediate frequency pulse corresponding to that received on the frequency f_1 , may be derived from one end of the inductor 219 and applied by a lead 225 to an amplifier tube 226, whereas the intermediate frequency pulse corresponding to that received on the frequency f_2 may be derived from the other end of the inductor 219 and applied by a lead 227 to an amplifier tube 228. The output circuits of the amplifier tubes 226 and 228 are connected through selective intermediate frequency transformers 230 and 231 respectively to rectifiers 232 and 233 respectively. Resistors 234 and 235, in circuits with the rectifiers 232 and 233, are connected respectively across terminals 24 and 25 and across terminals 26 and 27 which correspond to the terminals 24, 25, 26 and 27 of Fig. 1. The pulses are thus separated and made individually available as positive pulses to the timing comparator.

The operation of this embodiment is similar to that above described except that only a single receiver is used instead of the two receivers indicated in Fig. 1.

In the embodiment of Fig. 3 a pair of pulses on channels f_1 and f_2 are received and detected in the tuner 210 and detector 212 and are applied to the amplifier 216 through a double peaked transformer 215 with transmission peaks corresponding in spacing to the two frequencies f_1 and f_2 . These pulses are separated by the frequency discriminator circuit 217 and are individually amplified in the amplifiers 226 and 228. The amplifier outputs are rectified by the rectifiers 232 and 233 to produce voltage drops in the resistors 234 and 235 in the form of voltage pulses corresponding to the received pulses. The pulse received on the frequency f_1 is thus supplied to the terminals 24 and 25 and the pulse received on the frequency f_2 is supplied to the terminals 26 and 27. These terminals are connected to the timing comparator 32 as shown in Fig. 1 wherein their timing is compared and the relays 328 and 328a are selectively actuated in accordance with the pulse sequence.

It is to be understood that a plurality of channels may be used which may be pulsed in selected sequences for a multiple control. A pair of channels have been described for purposes of illustration only.

Although certain specific embodiments of the invention have been shown and described in detail, it is to be understood that the invention is not to be restricted thereto, but is only to be

limited in accordance with the scope of the following claims.

I claim as my invention:

1. A system responsive to a pair of pulses received in predetermined sequence over individual channels, comprising multivibrator circuit means responsive to the first received pulse of the pair being received on one channel to stretch the duration of said first pulse an amount to cause the same to overlap in time the later received pulse and non-responsive to the first received pulse being received on the other channel, whereby the pulses are made coincidental in time only on reception of the first pulse on said one channel, and a key circuit responsive to the combined effect of said coincidental pulses.
2. A system responsive to a pair of pulses received in predetermined sequence over individual channels, comprising multivibrator circuit means responsive to the first received pulse of the pair being received on one channel to stretch the duration of said first pulse an amount to cause the same to overlap in time the later received pulse and non-responsive to the first received pulse being received on the other channel, whereby the pulses are made coincidental in time only on reception of the first pulse on said one channel, a pair of space discharge devices having input circuits responsive to said coincidental pulses and biased to pass space current except when blocked by said coincidental pulses, and an output circuit responsive to the simultaneous blocking of said devices.
3. A system responsive to a pair of pulses received in predetermined sequence over individual channels, comprising multivibrator circuit means responsive to the first received pulse of the pair being received on one channel to stretch the duration of said first pulse an amount to cause the same to overlap in time the later received pulse and non-responsive to the first received pulse being received on the other channel, whereby the pulses are made coincidental in time only on reception of the first pulse on said one channel, a pair of space discharge devices having input circuits responsive to said coincidental pulses and biased to pass space current except when blocked by said coincidental pulses, a plate resistor carrying the space current of said devices and connected to cause a substantial increase in plate voltage when no space current flows, and an output circuit responsive to said substantial increase in voltage.
4. In a radio pulse receiver for receiving and separating a pair of pulses received on different radio frequency channels, a receiving circuit receptive of both of said channels and including means terminating in a detector connected to make both pulses available at different frequencies, a frequency discriminating circuit comprising a pair of tuned circuits including mutually coupled inductances connected together at their mid points, one of said tuned circuits being coupled to be fed by said detector and individual output circuits connected to opposite potential points of the other of said tuned circuits.
5. In a radio pulse receiver for receiving and separating a pair of pulses received on different radio frequency channels, a receiving circuit receptive of both of said channels and including means terminating in a detector connected to make both pulses available at different frequencies, a frequency discriminating circuit comprising a pair of tuned circuits including mutually coupled inductances connected together at their

mid points, one of said tuned circuits being coupled to be fed by said detector and individual output circuits connected to opposite potential points of the other of said tuned circuits, said output circuits each including a space discharge amplifier having an output circuit, a rectifier circuit coupled to said last circuit and including a resistor connected to carry rectified current for developing a potential drop representing said pulse.

6. A receiving system responsive to the sequences of a pair of pulses on different channels, comprising radio receiving circuits tuned to receive the respective channels and terminating in detector means making the pulses available at different frequencies, a comparator having a pair of channels connected to receive said pulses from said detector means, said channels having sequence discriminating means responsive to the sequence of said pulses and respectively responsive to reverse pulse sequences, and means actuated by the respective channels.

7. A receiving system responsive to the sequence of a pair of pulses on different channels, comprising radio receiving circuits tuned to receive the respective channels and terminating in detector means making the pulses available at different frequencies, a comparator having a pair of channels connected to receive said pulses from said detector means, said channels having sequence discriminating means responsive to the sequence of said pulses and respectively responsive to reverse pulse sequences, said last means including means in each channel to extend the period of one of said pulses an amount corresponding to the lag between pulses so that the two pulses are caused to overlap in time in one channel or the other according to their sequence, circuits responsive only to the coincidental effect of both pulses connected in said channels, and relay means responsive to said last circuits.

8. A receiving system responsive to the sequence of a pair of pulses on different channels, comprising radio receiving circuits tuned to receive the respective channels and terminating in detector means making the pulses available at different frequencies, a comparator having a pair of channels connected to receive said pulses from said detector means, said channels each having means to delay one pulse an amount to make the pulses coincidental when in corresponding sequence and being respectively responsive to reverse pulse sequences, and circuits responsive only to the coincidental effect of both pulses connected to be actuated by pulses in the respective channels.

9. A receiving system responsive to the sequence of a pair of pulses on different channels, comprising radio receiving circuits tuned to receive the respective channels and terminating in detector means making the pulses available at different frequencies, a comparator having a pair of channels connected to receive said pulses from said detector means, said channels each having means to delay one pulse an amount to make the pulses coincidental when in corresponding sequence and being respectively responsive to reverse pulse sequences, circuits responsive only to the coincidental effect of both pulses connected to be ac-

70 tuated by pulses in the respective channels, and relay means selectively actuated by said last circuits.

10. A system responsive to a pair of pulses received in predetermined sequence over individual frequency separated channels, comprising a multivibrator having only one condition of stable equilibrium to which it returns a predetermined time duration after departure therefrom and connected to one of said channels to cause said multivibrator to depart from said condition on receipt of one of said pulses thereover, whereby the output of said multivibrator stretches the duration of said one pulse received over said one channel by said predetermined time duration to overlap a later of said pair of pulses received on the other said channel, and a key circuit connected to the other of said channels and to said multivibrator and responsive to coincidence of said stretched and said other pulse, whereby said key circuit is actuated by the first received pulse of said pair being received on said first channel and the second received pulse of said pair being received on said second channel and non-actuated by the first received pulse of said pair being received on said second channel.

11. The system claimed in claim 10, further comprising a second multivibrator having only one condition of stable equilibrium to which it returns said predetermined time duration after departure therefrom and connected to the other of said channels to cause said second multivibrator to depart from its said condition on receipt of a pulse over said second channel, whereby the output of said second multivibrator stretches the duration of said other pulse received over said other channel by said predetermined time duration to overlap a later of said pair of pulses received over said one channel, and a second key circuit connected to said one channel and to said second multivibrator and responsive to coincidence of said other pulse stretched and said one pulse, whereby said second key circuit is actuated by the first received pulse of said pair being received on said second channel and the second received pulse of said pair being received on said first channel and non-actuated by the first received pulse of said pair being received on said first channel.
